ARC DISCHARGE DEVICE

Charles G. Smith, Medford, Mass., assignor to
 Raytheon Manufacturing Company, Newton,
 Mass., a corporation of Delaware

Application April 3, 1946, Serial No. 659,228

6 Claims. (Cl. 315—330)

1

This invention relates to arc discharge devices of the type employing pool type cathodes, and more particularly to means for controlling the arc cathode spot thereon.

Heretofore attempts to control currents by extinction of the arc discharge have required the use of complicated and relatively ineffective devices.

The primary object of the invention is to provide a device of the type described which positively and quickly extinguishes an arc spot.

Another object is to provide a device which does not require large capacity means or mechanical switching.

This invention will be best understood from the following description of an exemplification thereof, reference being had to the accompanying drawings, wherein:

Fig. 1 is a cross-sectional view of one embodiment of the invention;

Fig. 2 is a cross-section on line 2—2 of Fig. 1;

Fig. 3 is a partial cross-section on line 3—3 of Fig. 1;

Fig. 4 is a diagrammatic representation of a system with which the invention may be practiced;

Fig. 5 is a cross-section of the electromagnet adjacent the main envelope on line 5—5 of Fig. 1;

Fig. 6 is a greatly enlarged partial cross-section of Fig. 3 detailing the magnetic field; and

Fig. 7 is a simplified graph representing certain operational conditions of the invention.

Referring now more particularly to Fig. 1, the device comprises a substantially cylindrical vitreous envelope 10 having integral with the lower-most portion thereof and perpendicular to its axis a vitreous tubular member 11 closed at the free end thereof, the opposite end opening into said main envelope 10. Supported within said envelope by an electrically conductive member 12 embedded in said envelope is an anode 13, preferably of carbon. A resistance igniting electrode 14 supported within said envelope by an electrically conductive member 15 has its pointed portion partially immersed in the mercury liquid pool cathode 16.

Supported within tubular member 11 is an auxiliary electrode 17, said electrode being composed of carbon, for example, and supported by electrically conductive members 18 embedded in said envelope 11. Between said electrode 17 and closed end 19 of tubular member 11, and transversely positioned therein, is a perforate member 20. As illustrated in Fig. 2, said perforate member comprises a frame 21 of non-magnetic material, such as non-magnetic steel or the like. Inserted within a substantially rectangular opening in said frame is a plurality of slugs or bars 22 of magnetic material, which may be iron for example. The spaces between bars 22 are made sufficiently wide

2

so that capillary action of the mercury cathode between said bars does not interfere with the flow thereof and same can flow readily in the interstices of perforate member 20. However, it is possible to use nickel which is also magnetic and has the advantage that it can be wetted by the mercury cathode. Using nickel as the material for bars 22 allows closer spacing. The capillary action when the liquid can wet the grid bars permits the liquid to readily enter a confined space. The narrower spacing so provided steps up the efficiency of the extinguishing feature of the perforate member as the arc spot would be broken up in the narrower interstices of the perforate member and more readily extinguished. Perforate member 20 is supported within the tubular member by electrically conductive members 20A, said conducting members being embedded in sealed end 19 of tubular member 11.

20 Adjacent electrode 17 is placed an electromagnet 24, the field of which is in the plane of the surface of cathode 16, said electromagnet having two windings 25, 26 surrounding the two legs or poles 27, 28 as delineated in Fig. 5, the axis of the extended portions 29, 30 of said legs 27, 28 being transverse of the axis of said tubular member 11. Both windings 25, 26 are wound in a direction which would make legs 27, 28 south poles when said windings are energized as explained herein-after. Positioned adjacent perforate member 20 is a permanent magnet 31 forming a partial yoke around the tubular member 11, the axis of the field of said magnet 31 being at right angles to the vertical axis of said perforate member 20 so as to set up intense magnetic fields in spaces 22A between bars 22.

25 In connection with the foregoing paragraph, the effectiveness of magnet means 31 for inducing an intense field in the interstices 22A of the perforate member 21 will be discussed. The field thus induced in said interstices presents an arcuate front 44 to oncoming arc spot 45. Regardless of directions of path of the arc spot 45 toward the perforate member, when said spot enters the arcuate shaped field 44 it tends to travel, due to the effect inherent in retrograde motion of an arc spot in a magnetic field, along a path 46 in a direction normal to a tangent to said field 44 and is thus very effectively drawn 30 into the interstices 22A. Entry of the arc spot 45 into narrow interstices 22A causes abrupt extinction of said spot as the ions are rapidly diffused to the walls of bars 22. Because deionization proceeds at a rate greatly in excess of ionization 35 it becomes impossible to sustain the arc discharge. Rapid diffusion of the ions is due to the very narrow spacing 22A of the perforate member 20.

40 Fig. 3 is a cross-section of the tubular member taken longitudinally of said member and illustrates clearly the arrangement of non-magnetic

metal deflecting members 23. As indicated these members are affixed to frame 21 of perforate member 20 and the free ends of said deflecting members diverge toward the walls of tubular member 11 in a direction toward the opening in main envelope 10. As the arc spot or spots, as the case may be, race into tubular member 11 with a retrograde motion toward the perforate member, said arc spot or spots are guided into the interstices 22A of the perforate member with greater efficiency.

Retrograde motion is defined herein as the direction taken by an arc spot which is opposite to the electromagnetic push, the path an arc spot takes being along a line at right angles to the axis of said field. This retrograde motion is contrary to the usually understood behavior of an arc in a transverse field, said arc usually being considered as going in the direction of the forces applied to the ionized region. Furthermore, although the arc cathode spot races along the cathode surface in a retrograde direction, the mercury vapor from the arc spot moves away from the arc spot in a direction opposite the motion of the arc spot. The vapor therefore behaves as usually understood in a transverse magnetic field. Were this phenomenon not so and the vapor preceded the arc spot, said spot would never reach perforate member 20 and extinction could not take place. The motion of the vapor upon reaching the perforate member would be impeded and inasmuch as said spot is carried along by the vapor it would also stop.

Retrograde motion of an arc spot in the transverse magnetic field occurs at pressures below about 3 mm. of Hg for practically all spacings of anode and cathode, provided the magnetic field is between zero and 5000 gauss. If anode spacing and magnetic field strength are maintained constant while the pressure of the conducting gas or vapor is increased, there will be found a critical pressure at which retrograde motion ceases. Above this critical pressure, ordinary motion takes place.

To continue retrograde motion of the arc spot above the critical pressure herebefore mentioned, spacing of main electrodes 13 and 16 is decreased below the critical value of electrode spacing above recited. As illustrated in the graph of Fig. 7 in which P represents the pressures above the critical value hereinbefore recited and $1/d$ the reciprocal of the space below the critical value mentioned above, values above curve A, B will cause a reversal of retrograde motion of the arc spot and values below said curve will produce retrograde motion. Therefore, with spacing of the main electrodes 13 and 16 less than the critical value herein recited and a field within the critical range mentioned, pressure times the distance at which retrograde motion ceases is approximately a constant.

Fig. 4 is a diagrammatic representation of the device when practiced in connection with a resistance welding circuit. Battery 33 or other source of potential is connected to igniting electrode 14. In series with said battery is starting switch 34 which when operated impresses a potential impulse on igniting electrode 14 and causes an incipient arc cathode spot to appear on the surface of cathode 16. Anode 13 has a potential impressed on it from direct current input 35, through current limiting resistor 36, primary winding 37 of welding transformer 38, and winding 26 on electromagnetic pole 28. Auxiliary electrode 17 is impressed with a potential from

D. C. source 35 through current limiting resistor 39. Said last-named electrode 17 serves to pick up the main discharge between the anode 13 and the cathode 16 when the arc cathode spot is caused to move, under said electrode 17, in a direction toward the perforate member 20 and so functions to guide the cathode spot along a predetermined path. Potential to energize winding 25 on electromagnetic pole 27 is received from battery 40 or some other source of potential. Condenser 41 is shunted across series connected windings 26 and 37 and serves to cushion the electromotive force of the welding system when the current is interrupted.

Having described in detail the various structural components of the present device, the mode of operation of said device when practiced in connection with a welding circuit will be discussed.

Assume that the device is in a non-conducting state and pole 27 of the electromagnet 24 has induced therein a field through the medium of winding 25, said winding being energized by battery 40. As pointed out heretofore, winding 25 is wound in a direction so as to induce in said pole 27 a magnetic field which makes said pole a south pole. The field intensity of said pole 27 is about 5000 gauss, more or less.

Manipulating switch 34 impresses a potential impulse from battery 33 on igniting electrode 14 whereupon an incipient arc cathode spot is formed on the surface of cathode 16, and as soon as sufficient ionization takes place between these last-named electrodes, the discharge will begin to pass to anode 13, conduction will start and an arc spot capable of sustaining the discharge will be formed.

Immediately previous to the conduction period just recited, the magnetic field of pole 27, which is in the plane of the surface of cathode 16 and adjacent the opening 11A of the main envelope 10, confines the arc spot to a region substantially within the area where said spot is initiated. Were it not for this particular feature of the present device, the arc spot would start racing along the surface of the cathode into tubular member 11 toward perforate member 20. In order to control the extinguishing period of the device, the magnetic field of pole 27 is momentarily made a barrier to the motion of the arc spot. However, as the conduction cycle proceeds and current flows through primary winding 37 and thence through electromagnetic winding 26 on pole 28, a greater field is induced in pole 28 than that which is present in pole 27, and consequently pole 28 is now a south pole, the field reverses its direction in the plane surface of cathode 16 and the arc spot has imparted to it a retrograde motion toward perforate member 20. With the impetus given the arc spot by the field of electromagnet 24, the arc spot races along cathode surface 16, and comes under the influence of the field of magnet 31 and into the interstices 22A of perforate member 20. The field of magnet 31 may be of the order of about 5000 gauss or less. The arc spot upon entering said interstices 22A is abruptly extinguished.

Upon extinction of the arc spot, the current is quickly interrupted, causing a collapse of the field in winding 37 of transformer 38, a transfer of energy to the secondary 42 and a flow of current through the work 43. The cycle is again repeated when desired. The actual operation of resistance welding circuits being well known to those versed in the art, no attempt is made to discuss the details pertaining to the equipment involved in such operation.

The arc spot on a mercury pool is of the highly mobile type which moves rapidly over the surface of the cathode. This same type of arc spot can be initiated on other materials, such as copper, aluminum and the like. Such highly mobile types of arc spot on these materials perform along the same principles with respect to retrograde motion as described above in connection with mercury pool cathodes.

Having described and illustrated the present invention, it will be apparent to those skilled in the art that various changes and modifications may be made therein without departing from the spirit of the invention or from the scope of the appended claims.

What is claimed is:

1. An arc discharge device comprising: an envelope having an auxiliary portion extending substantially perpendicular to the axis thereof; an anode supported within said envelope; a liquid cathode disposed within said envelope; means for initiating an arc spot on the surface of said cathode; a perforate member disposed within the auxiliary portion of said envelope, parallel to the axis and perpendicular to the surface of said cathode; magnetic means disposed adjacent said perforate member; and means for energizing said magnetic means to urge said arc spot into the interstices of said perforate member, said perforate member having induced in the interstices thereof a magnetic field of sufficient magnitude to extinguish said arc spot.

2. An arc discharge device comprising: an envelope having an auxiliary portion extending substantially perpendicular to the axis thereof; an anode supported within said envelope; a liquid cathode disposed within said envelope; means for initiating an arc spot on the surface of said cathode; a perforate member disposed within the auxiliary portion of said envelope; said perforate member being parallel to the axis and perpendicular to the surface of said cathode, and partly immersed in said cathode, said perforate member consisting of a plurality of spaced parallel bars; magnetic means disposed adjacent said perforate member; and means for energizing said magnetic means to urge said arc spot into the interstices of said perforate member to extinguish said arc spot.

3. An arc discharge device comprising: an envelope having an auxiliary portion extending substantially perpendicular to the axis thereof; an anode supported within said envelope; a liquid cathode disposed within said envelope; means for initiating an arc spot on the surface of said cathode; a perforate member disposed within the auxiliary portion of said envelope, parallel to the axis and perpendicular to the surface of said cathode; said perforate member consisting of a non-magnetic frame having a plurality of parallel magnetic members set therein, said members being spaced a distance apart sufficient to permit the free flow of said cathode material therebetween; magnetic means disposed adjacent said perforate member; and means for energizing said magnetic means to urge said arc spot into the interstices of said perforate member to extinguish said arc spot.

4. An arc discharge device comprising: an envelope having an auxiliary portion extending substantially perpendicular to the axis thereof; an anode supported within said envelope; a liquid cathode disposed within said envelope; means for initiating an arc spot on the surface of said cathode; a perforate member disposed within the

auxiliary portion of said envelope, parallel to the axis and perpendicular to the surface of said cathode; said perforate member being composed of a material capable of being wetted by said cathode to permit the free flow thereof in the interstices of said perforate member; magnetic means disposed adjacent said perforate member; and means for energizing said magnetic means to urge said arc spot into the interstices of said

10 perforate member to extinguish said arc spot.

5. An arc discharge device comprising: an envelope having an auxiliary portion extending substantially perpendicular to the axis thereof; a liquid cathode disposed within said envelope; an anode supported within said envelope, in spaced relationship to said cathode; an igniting electrode, supported within said envelope adjacent said cathode, for initiating an arc spot on the surface of said cathode; means, disposed within the auxiliary portion of said envelope, for establishing a magnetic field in the plane of the surface of said cathode; the polarity and intensity of said field being such as to impart retrograde motion to said arc spot and draw the same into said field; and means, including a perforate member disposed within the auxiliary portion of said envelope and within the path of said magnetic field, for dispersing the ionized atmosphere adjacent said arc spot and thereby extinguish the same.

30 6. An arc discharge device comprising: an envelope having an auxiliary portion extending substantially perpendicular to the axis thereof; a liquid cathode disposed within said envelope; an anode supported within said envelope, in spaced relationship to said cathode; an igniting electrode, supported within said envelope adjacent said cathode, for initiating an arc spot on the surface of said cathode; means, adjacent the 35 region of said cathode in which said arc spot is initiated, for establishing a first magnetic field in the plane of the surface of said cathode; the polarity and intensity of said first field initially being such as to repel said arc spot and maintain the same in said region of its initiation; means, disposed within the auxiliary portion of said envelope and spaced from said first-named means on the side of the latter opposite to said region of arc spot initiation, for establishing a second magnetic field in the plane of the surface of said cathode; the polarity and intensity of said second field being such as to be adapted to impart retrograde motion to said arc spot and draw the same into said field; means for reversing the polarity of said first magnetic field, thereby to impart retrograde motion to said arc spot and urge the same toward said second-named means; and means, including a perforate member disposed within the auxiliary portion of said envelope and within the path of said second magnetic field, for dispersing the ionized atmosphere adjacent said arc spot and thereby extinguish the same.
